United States Patent Office

Des. 211,154
Patented May 28, 1968

211,154

DISPENSING CONTAINER FOR LIQUIDS OR THE LIKE

Joseph Charles Pizzurro, Scarsdale, N.Y., assignor to Precision Valve Corporation, Yonkers, N.Y., a corporation of New York

Filed July 25, 1967, Ser. No. 7,967

Term of patent 14 years

(Cl. D9—53)

FIG. 1

FIG. 2

FIG. 5

FIG. 3

FIG. 1 is a perspective view of a dispensing container for liquids or the like, showing my new design;
FIG. 2 is a top plan view;
FIG. 3 is a front elevational view;
FIG. 4 is a side elevational view; and
FIG. 5 is a rear elevational view thereof.
I claim:

The ornamental design for a dispensing container for liquids or the like, as shown.
